(57) **CLAIM**

The ornamental design for a slipper as shown and described.

DESCRIPTION

FIG. 1 is a perspective view of a slipper showing my new design.

FIG. 2 is another perspective view thereof;

FIG. 3 is a top view thereof;

FIG. 4 is a bottom view thereof;

FIG. 5 is a left view thereof;

FIG. 6 is a right view thereof;

FIG. 7 is a front view thereof; and,

FIG. 8 is a rear view thereof.

The broken lines in the drawings depict portions of the slipper that form no part of the claimed design.
